GOLF PRACTICING DEVICE FOR DEVELOPING THE PROPER STANCE AND STROKE FOR PUT-TING

Vernon Richard Nelson, 8515 N. 58th St.,
Milwaukee, Wis.

Filed June 26, 1963, Ser. No. 75,525

Term of patent 14 years

(Cl. D34—5)

FIG. 1 is a top plan view of a golf practicing device for developing the proper stance and stroke for putting showing my new design;

FIG. 2 is a side elevation;

FIG. 3 is a bottom view;

FIG. 4 is an end view taken along line 4—4 of FIG. 1; and

FIG. 5 is an end view taken along line 5—5 of FIG. 1.

I claim:

The ornamental design for a golf practicing device for developing the proper stance and stroke for putting, substantially as shown.
